NIGHT DRIVING GLASSES

Otto W. Githens, New York, N. Y., and Wallace W. Ward, Bloomfield, N. J., assignors to Utilitron Incorporated, New York, N. Y., a corporation of New York

Application February 8, 1951, Serial No. 14,141

Term of patent 14 years

(Cl. D57—1)

To all whom it may concern:

Be it known that we, Otto W. Githens and Wallace W. Ward, both citizens of the United States and residents, respectively, of the city, county, and State of New York, and Bloomfield, in the county of Essex, State of New Jersey, have invented a new, original, and ornamental Design for Night Driving Glasses, of which the following is a specification, reference being had to the accompanying drawing, forming part hereof, in which:

Fig. 1 is a front view of the night driving glasses showing our new design in a folded condition;

Fig. 2 is a front elevation of the same with the respective lenses extended to the outermost position with longitudinal adjustment; and

Fig. 3 is a plan view of the same with the lenses in the line of vision, as used.

We claim:

The ornamental design for night driving glasses, as shown and described.

OTTO W. GITHENS.
